Washing Machine,

Patented Apr. 22, 1830.

Received a number of the following from the Steuben County, N.Y. Clerk

SIXTY-FIVE.

The Schedule of suits in these Letters Patent and writing of the same concerning a Improvement in the construction of the said Apparatus Shewing how all of his improvement in the Machine for Washing Clothes.

Specification. That of George W. Thurber of the Town of Painted Post, Steuben County and State of New York have made an improvement in the machine for Washing Clothes, which is described as follows. This Washing machine consists of the following principal parts. 1. The Water-tight Box. 2. The Barrel or cylinder for holding the clothes. 3. The stand. 1. The Water-tight Box is constructed by framing together by dovetailing mortising &c two end pieces about twenty two inches long and about the same depth, 1 inch thick, to two side pieces about 2 feet long 11 inches wide and 1 inch thick, having a curved part or end of wood or metal forming the bottom and rising gradually the rear end of the barrel to be hereafter described. The whole is covered and made perfectly watertight. There is a plug or cork at the end near the bottom for drawing off the water. 2. The Barrel or cylinder. The interior of the barrel is a parallelogram formed by uniting together two end pieces about 15 inches square, and one inch connected by 11 slats or bars about 20 inches long, 7 7/16 inches wide, 3/8 inch thick and perforated with a sufficient number of holes 1 1/4 inch in diameter. On the outside are four brackets one over each of the perforated slats, for raising the water. On each ^{end} the end of the water box is inserted into the end of the barrel by means of which & a screw it is made to revolve on its axis in the curved bottom & to which it is adapted. There are also a number of bars with springs, or boards, perforated with holes to cover the other parts of the barrel, and between the perforated slats before mentioned. One side of the bars forming a movable door for admitting and taking out again the clothes to be washed. It is fastened in any convenient way. 3. The stand is made by either fastening on legs to the water box or making it independent of the box.

Operation. The clothes to be washed are placed in the barrel. The water and soap are put into the water box. The barrel is then turned with an irregular motion so as to revolve the clothes and let them fall again to the bottom, during this operation the water or soap is beaten water entering and passing on the clothes through perforations in the barrel. A number of balls of wood of about 2 inches in diameter are put in with the clothes which and with anything else that is to be washed they are taken out of the barrel & the water

drawn off. What I claim as my invention is the combination of the several parts of the Improvement described Machine & the manner of using it. I wish to illustrate my invention by referring to the model & drawing of the same deposited in the Patent Office.
I do testimony that the foregoing is a true specification of my invention & have made and to the best of my knowledge signed my name before two witnesses at the City of Washington this 12th day of April 1830.
